UNITED STATES PATENT OFFICE.

ADOLPH C. RECKER, OF OAKVILLE, CONNECTICUT, ASSIGNOR TO CHASE COMPANIES INC., OF WATERBURY, CONNECTICUT, A CORPORATION.

FORCE-FEED OIL CAN.

Application filed December 15, 1924. Serial No. 755,908.

Fig. 1 is a view in side elevation of my improved force-feed oil-can.

Fig. 2 is a view thereof in longitudinal, central section on an enlarged scale.

Fig. 3 is a sectional view on the line 3—3 of Fig. 2, but omitting the spring.

Fig. 4 is an underside view of the cap and spout, with the spring assembled therewith.

My invention relates to an improvement in force-feed oil-cans, the object being to produce, at a low cost for manufacture, a convenient, durable, and reliable can constructed with particular reference to fewness of parts and simplicity of construction.

With these ends in view, my invention consists in a force-feed oil-can having certain details of construction and combinations of parts as will be hereinafter described and particularly pointed out in the claims.

In carrying out my invention, as herein shown, I form, upon the body 5 of the can, a sufficiently large and long, cylindrical neck 6 to provide a piston-chamber 7 in which I locate a piston 8 substantially corresponding to it in diameter and co-acting directly with the inner faces of its side-walls, i. e., with the side-walls of the neck of the body of the can. As herein shown, the said piston 8 is mounted between metal disks 9 screwed upon the threaded upper end of a piston-rod 10 in a guide-tube 11 mounted in the center of the recessed bottom 12 of the body 5 of the can, the projecting lower end of the piston being provided with the usual push-button 13. A jam-nut 14 holds the piston-disks 8 in place upon the rod 10. The spout 15 is mounted in a cap 16 having a threaded skirt 17 screwed over threads rolled into the outer end of the neck 6. A packing-washer 18, interposed between the cap and the inwardly-turned edge of the neck, prevents leakage.

The piston is returned into its normal position and held therein by means of a helical spring 19 interposed between it and the cap 16, the lower end of the said spring being turned inwardly and then passed axially outwardly through the spring and made long enough, as at 20, to extend through the tip of the spout when the spring is compressed, whereby the spout is kept from being clogged.

In its normally retired position, in which it rests upon the guide-tube 11, the piston

8 is located below the curve formed in the sheet-metal body of the can, where the tapering shoulder thereof merges into its cylindrical neck 6. This curved surface is engaged by the edge of the piston and serves to center the same as it enters the neck which forms the piston-chamber of the can.

In using my improved can, it is tipped enough to cause oil to flow into the piston-chamber 7, after which the button 13 is pushed to operate the piston 8 against the tension of the spring 19 in forcing the oil out of the spout. As soon as pressure upon the button 13 is removed, the spring reasserts itself to retire the piston into its charging position, in which it is shown in Fig. 2.

By enlarging and lengthening the neck of the body of the can, so as to adapt it to be utilized as the forcing-chamber, I avoid the complication of employing a special cup located within the neck for the purpose. Also, the extension of the lower end of the spring into the spout provides simple means of preventing the same from being clogged.

I am aware that force-feed oil-cans have been provided with cleaning wires extending through their spouts for preventing the same from being clogged. I am also aware that the piston-chambers of force-feed oil-cans have been located adjacent their spouts, as well as at the bottoms of their fonts, and that such oil-cans have been provided with helical springs for holding their pistons in their retired positions. I do not, therefore, claim any of these features broadly, but

I claim:

1. In a force-feed oil-can, the combination with a body having a cylindrical neck merging into the body by an oblique wall and forming a piston-chamber, of a piston positioned to co-act directly with the said neck, a piston-rod, the upper end of which mounts the said piston and the lower end of which projects through the bottom of the can for its manual operation, a combined cap and spout applied to the outside of the neck, and a helical spring interposed between the said cap and the upper face of the said piston for holding the latter in its retired position.

2. In a force-feed oil-can, the combination with a body having a cylindrical neck merging into the body by an oblique wall and forming a piston-chamber, of a piston posi-

tioned to co-act directly with the said neck, a piston-rod, the upper end of which mounts the said piston and the lower end of which projects through the bottom of the can for its manual operation, a combined cap and spout applied to the outside of the neck, and a helical spring interposed between the said cap and the upper face of the said piston for holding the latter in its retired position,

the inner end of the spring being turned inwardly and passed axially outward through the coil thereof and extended substantially to the end of the said spout to act as a cleaning-wire.

In testimony whereof, I have signed this 15 specification.

ADOLPH C. RECKER.
